INTERNAL-COMBUSTION HEATER WITH EXPANSIBLE FUEL RESERVOIR

Henry J. De N. McCollum, Chicago, Ill.; Thelma McCollum, executrix of said Henry J. De N. McCollum, deceased, assignor to Stewart-Warner Corporation, Chicago, Ill., a corporation of Virginia

Application May 7, 1943, Serial No. 486,019

6 Claims. (Cl. 126—116)

1

My invention relates to heating apparatus and more particularly to an internal combustion type of heating apparatus especially adapted for, but not limited to, use on automobiles.

An object of my invention is to provide a new and improved heating apparatus for automobiles which will operate independently of the automobile engine cooling system.

Another object of my invention is to provide new and improved heating apparatus which will continue to operate after the automobile engine has been stopped.

Another object of my invention is to provide automobile heating apparatus of the internal combustion type having a pressure reservoir providing for operation of the heating apparatus independently of the automobile engine.

Another object of my invention is to provide new and improved heating apparatus of the internal combustion type which is supplied with fuel from the engine fuel pump, but which will operate for a predetermined length of time after this fuel pump is stopped.

Other objects and advantages will become apparent as the description proceeds.

In the drawings:

Fig. 1 is a diagrammatic representation of my invention showing the internal combustion heater in longitudinal section; and

Fig. 2 is a wiring diagram of the heater of the present invention.

In Fig. 1, I have indicated a conventional automobile engine 10 as having an intake manifold 12 to which the usual carburetor 14 is attached. An air cleaner 16 is affixed to the air inlet of the carburetor 14 and fuel is supplied to this carburetor through a pipe 18 which connects the usual float bowl 20 with a fuel pump 22. A second pipe 24 connects the fuel pump 22 with the usual gasoline tank 26. The pump 22 is preferably of the conventional diaphragm type in which the diaphragm is moved on its intake stroke by an engine driven cam and is returned by a spring which determines the pressure under which the fuel is forced to the engine carburetor.

A T 28 is located intermediate the pipe 18 and serves to connect this pipe with a resilient fuel reservoir indicated generally by the reference numeral 100 and a solenoid valve 30 in a fuel supply line 32 leading to a fuel jet 34 located in the inlet end of the induction tube 36 of a heater indicated generally by reference numeral 38. A filter 40 is preferably interposed between the solenoid valve 30 and jet 34 to protect the latter against

any dirt or other impurities contained in the gasoline.

The heater 38 is of the internal combustion type and comprises in general a casing 42 having an inlet end 44 attached to the discharge outlet 46 of a blower 48. This blower delivers air to the lefthand end of the casing 42 under low pressure and may be of any conventional type, such as the centrifugal type shown in the drawing. An electric motor 50 drives the blower 48 and is designed to operate from the usual automobile electrical system.

A combustion chamber 52 is located in the casing 42 and supplied with a mixture of fuel 15 and air by the induction tube 36. This combustion chamber has a circular wall and the induction tube 36 delivers the combustible mixture in a direction tangential to this wall so that the combustible mixture tends to whirl about the longitudinal axis of the combustion chamber. The tube 36 has a portion of appreciable length located within the combustion chamber and this portion of the tube serves as a means for pre-heating the combustible mixture.

25 A housing 54 is attached to the lefthand end of the combustion chamber and provides a pocket 56 which communicates with the combustion chamber through an opening 58 in the end wall thereof. An igniter block 60 is threaded into a wall of the housing 54 and has an igniting coil 62 for igniting combustible mixture in the pocket 56. It will be apparent from an inspection of Fig. 1 that the outlet end 58 of the induction tube 36 is directed toward the opening 58 whereby 30 mixture leaving this induction tube tends to enter the pocket 56 where it will come in contact with the igniting coil 62.

Hot products of combustion issue from the righthand end of the combustion chamber 52 40 through the opening 64 in an annulus 66 which serves to prevent the escape of liquid fuel from the combustion chamber. These hot products of combustion enter the lefthand end of a cylindrical sleeve 68 located in a circularly arranged series 45 of ventilating air tubes 70 mounted in partitions 72 and 74. The hot products of combustion entering the sleeve 68 are mixed therein with secondary air admitted to the large end of this sleeve through openings 76 in the partition 72.

50 The mixture of hot products of combustion and secondary air is discharged from the righthand or smaller end of the sleeve 68 and flows backwardly along this sleeve, as shown by the arrows in Fig. 1. The ventilating air tubes 70 are located between the sleeve 68 and a generally cylind-

drical casing 78 and these tubes are in spaced relation to the sleeve and casing and to each other so that the hot gases issuing from the righthand end of the sleeve 68 can completely surround the ventilating air tubes 70 as these gases flow to the left, as viewed in Fig. 1. The casing 78 has an annular enlargement 80 which functions somewhat as an exhaust manifold. The cooled gases flow into this enlargement 80 and are discharged to atmosphere through an exhaust pipe 82 communicating with this enlargement.

Part of the ventilating air supplied by the blower 48 flows upwardly in a sheet metal sleeve 84 surrounding the igniter plug 60. When the heater is first turned on, the heat of the igniter plug serves to preheat the air flowing between this plug and the sleeve 84 and since this air is used for combustion purposes, such preheating facilities prompt ignition of the fuel mixture in the combustion chamber. This combustion air flows from the upper end of sleeve 84 through a passage 86 provided by a sheet metal cover 88 and into the upper end of the induction tube 36. This induction tube has an appreciable portion of its length in the combustion chamber and after the heater has been in operation for a short length of time, this portion of the induction tube supplies the requisite preheating to the fuel mixture before it enters the combustion chamber.

It is to be particularly noted that the induction tube 36 has no restriction therein and affords a minimum resistance to air flow therethrough. The passages leading to the upper end of this induction tube are large and offer minimum resistance to flow so that a low pressure blower is capable of supplying adequate air for combustion purposes as well as for ventilating purposes.

Most of the air supplied by the blower 48 is used for ventilating and heating purposes and passes around the combustion chamber 52 from which it absorbs some heat. This air then enters the ventilating air tubes 70 where it receives further heat from the hot products of combustion discharged from the combustion chamber. The heated air leaving the righthand ends of the ventilating air tubes 70 then enters the tapered outlet end 90 of the heater casing and passes through one or more outlets into the passenger space or spaces of the automobile. Such outlets, of course, may be controlled with any usual or desired shutter arrangement.

The heat exchange means for transferring the heat from the hot products of combustion to the ventilating air is especially designed to offer low resistance to flow of this ventilating air and also to the products of combustion issuing from the combustion chamber. This heat exchange means cooperates with the other features of the heater which permit the use of a low pressure blower requiring the minimum of operating current for its driving motor. The electrical igniter, in accordance with usual practice, is provided with a thermostatic switch which disconnects this igniter from its source of current when the heater attains normal operating temperature so that the entire heating apparatus places a minimum drain on the automobile electrical system. Certain features of the heater shown and described herein are claimed in my co-pending application, Serial No. 479,039, filed March 13, 1943, now abandoned.

In operating an automobile, it frequently happens that the automobile is stopped but the occupants of the vehicle remain therein while waiting for a friend or relative to arrive on a train or while one member of the party runs an errand

or is otherwise absent for a relatively short period of time. While the vehicle is thus stopped, it is desirable to turn off the automobile engine, but this can not be done and the occupants of the automobile remain comfortable in cold weather unless some heating means independent of the engine is provided. The resilient fuel reservoir 100 which I have illustrated is intended to provide for situations of this kind and will allow the heater to continue to operate for as much as half an hour or more after the automobile engine has been stopped.

This resilient reservoir may assume numerous forms, but in the particular embodiment shown, this reservoir which is interposed between the fuel pump 22 and solenoid valve 30 is composed of upper and lower sheet metal cups 102 and 104 secured together by bolts 106, or in any other suitable manner.

A flexible diaphragm 108 divides the resilient reservoir into upper and lower chambers 110 and 112, respectively. The periphery of this diaphragm is gripped between radially projecting flanges 114 and 116 provided by the cups 102 and 104, respectively, and the center portion of this diaphragm is gripped between sheet metal plates 118 and 120 clamped together by bolt 122 and nut 124. A spring 126 is confined between plate 118 and cup 102 and serves to urge the central portion of the diaphragm downwardly to expel fuel from the chamber 112 therebeneath.

The cup 102 has a depression 128 forming a guide for the upper end of the spring 126 and a centrally located upwardly extending portion 130 provided with vent openings 132 for the upper chamber 110. A cover 134 is affixed to this extension and protects the openings 132 against dirt and dust. This cover has a sleeve 136 forming a guide for the upper end of the bolt 122 which actuates an automatic switch that serves to stop the heater whenever the fuel in the chamber 112 is exhausted.

A bracket 138 is attached to the cup 102 and carries insulating blocks 140 to which is affixed an electrical terminal 142 and one end of a spring switch member 144. The other end of this switch member carries a contact 146 which is urged downwardly by the resilience of the spring member 144. The upper end of the bolt 122 carries an insulating block 148 supporting a second switch contact 150 which moves up and down with the central portion of the diaphragm 108. When the chamber 112 beneath this diaphragm contains fuel, the contacts 146 and 150 are in engagement as shown in Fig. 1. When the fuel in the lower chamber 112 is consumed and no additional fuel is supplied thereto by the fuel pump 22, the central portion of the diaphragm 108 and contact 150 descend. Contact 146 descends with contact 150 until switch member 144 engages stop pin 152 whereupon these contacts separate to break the electrical circuit therethrough.

The arrangement of the automatic switch controlled by the pressure reservoir in the operating circuit for the heater is best shown in the wiring diagram of Fig. 2. In this diagram the usual automobile battery is indicated by reference numeral 154 and it is to be understood that this battery may be connected to the automobile starting, lighting and ignition systems in the conventional manner. One side of the battery is grounded at 156 and the other side of this battery is connected to a manual switch 158 which is the operating switch for starting and stopping the operation 75 of the heating apparatus. This switch controls

communication between the automobile battery and the electric motor 50 for the blower, the igniter coil 62 and the solenoid valve 30. The motor 50, coil 62 and solenoid valve 30 are all grounded, as indicated at 160, 162 and 164, respectively, and the usual thermostatic switch 166 is located in the igniter circuit to disconnect the igniter coil 62 from the battery when the heater attains normal operating temperature.

The automatic switch, comprising the resilient switch member 144 and contacts 146 and 150, is interposed between the manual switch 158 and the motor 50, coil 62 and solenoid valve 30, so that the last three elements are disconnected from the automobile battery whenever this automatic switch is opened, regardless of the position of the manual switch 158.

The spring 126 of the resilient reservoir 100 is slightly weaker than the spring of the fuel pump 22 so that when this pump is operating fuel is supplied to the engine carburetor and forced into the lower chamber 112 of the reservoir 100. This pushes the central portion of the diaphragm 108 upwardly against a spring 126, which is preferably so designed that it exerts a uniform force on the central portion of the diaphragm for all positions of this central portion. As long as the engine is operating, therefore, the reservoir 100 is ordinarily filled to its maximum capacity. This capacity may be sufficient to hold any predetermined amount of fuel, it usually being sufficient to provide for approximately one-half hour of heater operation after the automobile engine has stopped. In a particular size and type of heater I have found that a capacity of eight ounces of fuel will provide for a heater operation of somewhat more than one-half hour.

When it is desirable to have heat in the passenger compartment of the automobile, the operator closes the switch 158. This opens solenoid valve 30, starts blower motor 50 and supplies current to ignition coil 62. The heater thereupon begins to operate and as soon as it attains normal operating temperature, thermostatic switch 166 cuts out igniter coil 62 to reduce the drain on the automobile battery. Since the heater offers minimum resistance to air flow therethrough, the blower motor 50 may be made of minimum size and itself consumes little current. As long as the automobile engine operates, fuel will be supplied to compartment 112 as fast as it is consumed by the heater and this compartment will remain completely filled. If the engine is stopped, no additional fuel will be supplied to the compartment 112, but the valves in the carburetor float bowl and outlet of the engine fuel pump will prevent reverse flow of fuel from the compartment 112 of the pressure reservoir.

Stoppage of the automobile engine, however, will not interfere with the operation of the heating apparatus, as the downward force exerted by the spring 126 on the diaphragm 108 will force fuel from the chamber 112 to the jet 34 so that the heater will continue to be supplied with a combustible mixture as long as any fuel remains in the chamber 112. The period of time throughout which the heater will continue to operate after the automobile engine has been stopped will, of course, depend upon the fuel capacity of the pressure reservoir and, as previously stated, it is usually desirable to make this capacity such that the heater will continue to operate from one-half hour to a full hour.

If the automobile engine is not started before the fuel in the resilient reservoir is exhausted, the

descent of the diaphragm will open the automatic switch contacts 146 and 150 just before the fuel in the resilient reservoir is completely exhausted. This opening of the automatic switch will stop the motor 50 and result in closing of the solenoid valve 30, but will have no immediate effect on the igniter coil 62, since this coil is already disconnected from the battery by the open thermostatic switch 166. However, when this thermostatic switch cools down and closes, no current can flow to the igniter coil because of the open contact 146 and 150.

If the manual switch 158 is left closed and the motor is again started, the engine fuel pump 22 will force fuel into the chamber 112 of the resilient reservoir to raise the diaphragm and close the automatic switch contacts 146 and 150. This will result in re-starting the heater, but if further heat is not required the operator may stop the heater by opening the manual switch 158.

From the foregoing it will be apparent that the automatic switch associated with the resilient reservoir does not interfere with the operation of the heater whenever the automobile engine is operating, or as long thereafter as there is fuel in the chamber 112. As soon as the fuel in this chamber becomes exhausted, the automatic switch contacts 146 and 150 are opened to prevent unnecessary drain on the automobile battery and also to protect the motor 50 and ignition coil 62 against unnecessary operation. The particular resilient reservoir shown has a spring pressed diaphragm, but any other equivalent resilient means could be used in lieu thereof, such for example, as a closed air dome.

My new and improved heating apparatus is particularly adapted for use on automobiles but may be applied with equal facility to other vehicles or for stationary use. It is to be understood that my invention is not limited to the particular details shown and described, but may assume numerous other forms and that the scope of my invention is defined by the following claims.

I claim:

1. Heating apparatus of the class described, comprising an internal combustion heater, an electrical igniter therefor, a pump for supplying fuel to said heater, a pipe line connecting said pump to the heater, a fuel reservoir interposed in said pipe line between the pump and the heater, said reservoir comprising a fuel chamber having a flexible diaphragm forming one wall of said chamber, spring means constantly urging said diaphragm against the fuel in said chamber to provide pressure for feeding fuel from the reservoir to the heater when the pump is not operating, and switch means supported in fixed relation to said reservoir and connected to said diaphragm for actuation thereby to open the ignition circuit when the quantity of fuel in the chamber falls below a predetermined minimum.

2. Heating apparatus of the class described, comprising an internal combustion heater, a pump for supplying fuel to said heater, a pipe line connecting said pump to the heater, a fuel reservoir interposed in said pipe line between the pump and the heater, a spring closed valve in the pipe line between the reservoir and the heater and electrically operable means for opening said valve, said reservoir comprising a fuel chamber having a flexible diaphragm which forms one wall of said chamber, spring means constantly urging said diaphragm against the fuel in said chamber to provide pressure for feeding fuel from the reservoir to the heater when the pump is not

operating, and switch means supported in fixed relation to said reservoir and connected to said diaphragm for actuation thereby to open the circuit of said electrical means, causing said valve to close when the quantity of fuel in the chamber falls below a predetermined minimum.

3. Heating apparatus of the class described, comprising an internal combustion heater, a pump for supplying fuel to said heater, an electrically-driven blower for supplying combustion and ventilating air to said heater, a pipe line connecting said pump to the heater, a fuel reservoir interposed in said pipe line between the pump and the heater, said reservoir comprising a fuel chamber having a flexible diaphragm forming one wall of said chamber, spring means constantly urging said diaphragm against the fuel in said chamber to provide pressure for feeding fuel from the reservoir to the heater when the pump is not operating, and switch means supported in fixed relation to said reservoir and connected to said diaphragm for actuation thereby to open the circuit of said electrically-driven blower when the quantity of fuel in the chamber falls below a predetermined minimum.

4. Heating apparatus of the class described comprising an internal combustion heater which includes electrically energized means adapted to interrupt operation of the heater when de-energized, a pump for supplying fuel to said heater, a pipe line connecting said pump to the heater, a fuel reservoir interposed in said pipe line between the pump and the heater, said reservoir comprising a fuel chamber of sufficient volume to sustain operation of said heater for a period after operation of the pump is discontinued, said chamber having a flexible diaphragm forming one wall of said chamber, spring means constantly urging said diaphragm against the fuel in said chamber, and switch means connected to said diaphragm for actuation thereby to open the circuit of said electrically energized means when the quantity of fuel in the chamber falls below a predetermined minimum.

5. Heating apparatus of the class described comprising an internal combustion heater, an electrical igniter therefor, a pump for supplying fuel to said heater, a pipe line connecting said pump to the heater, a fuel reservoir interposed in said pipe line between the pump and the heater, a spring closed valve in the pipe line between the

reservoir and the heater and electrically operable means for opening said valve, an electrically driven blower for supplying combustion and ventilating air to said heater, said reservoir comprising a fuel chamber having a flexible diaphragm which forms one wall of said chamber, spring means constantly urging said diaphragm against the fuel in said chamber to provide pressure for feeding fuel from the reservoir to the heater when the pump is not operating, a source of electrical energy and a circuit which includes said energy source, said electrical igniter, said valve operating means, and said blower, and switch means operatively connected to said diaphragm for actuation thereby to open the said circuit when the quantity of fuel in said chamber falls below a predetermined minimum.

6. Heating apparatus of the class described comprising an internal combustion heater, means for supplying combustion and ventilating air to said heater, a reservoir comprising a pair of cups having a diaphragm clamped between them to form a fuel chamber and a spring chamber, a pump for supplying fuel to said heater connected into said fuel chamber and a pipe extending from said chamber to the heater, a spring in the spring chamber interposed between the diaphragm and one of said cups and urging the diaphragm against the fuel in the fuel chamber to provide pressure for feeding the fuel from the reservoir to the heater, switch means controlling said air supply means and connected to said diaphragm for actuation thereby, said switch means being adapted to be opened by movement of the diaphragm when the quantity of fuel in said fuel chamber falls below a predetermined minimum, said air supply being shut off by said opening of the switch means.
